Primary Examiner — Michael C Stout*Assistant Examiner* — Fitzgerald L Butac(74) *Attorney, Agent, or Firm* — Georgi Korobanov(57) **CLAIM**

The ornamental design for a heavy duty pneumatic can crusher, as shown and described.

DESCRIPTION

FIG. 1 is a perspective view of a heavy duty pneumatic can crusher showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines show portions of a heavy duty pneumatic can crusher which form no part of the claimed design.

1 Claim, 7 Drawing Sheets(56)
